CLAIM

The ornamental design for a closet drawer, as shown and described.

DESCRIPTION

FIG. 1 is a top, front, right side perspective view of a first embodiment of a closet drawer;

FIG. 2 is a front elevational view thereof;

FIG. 3 is a rear elevational view thereof;

FIG. 4 is a left side elevational view, the right side being a mirror image thereof;

FIG. 5 is a top view thereof;

FIG. 6 is a bottom view thereof;

FIG. 7 is a top, front, right side perspective view of a second embodiment thereof;

FIG. 8 is a front elevational view thereof;

FIG. 9 is a rear elevational view thereof;

FIG. 10 is a left side elevational view, the right side being a mirror image thereof, the top and bottom views being identical to FIGS. 5 and 6 respectively;

FIG. 11 is a top, front, right side perspective view of a third embodiment thereof;

FIG. 12 is a front elevational view thereof;

FIG. 13 is a rear elevational view thereof;

FIG. 14 is a left side elevational view, the right side view being a mirror image thereof, the top and bottom views being identical to FIGS. 5 and 6;

FIG. 15 is a top, front, right side perspective view of a fourth embodiment thereof;

FIG. 16 is a front elevational view thereof;

FIG. 17 is a rear elevational view thereof; and,

FIG. 18 is a left side elevational view, the right side view being a mirror image thereof, the top and bottom views being identical to FIGS. 5 and 6.
